B. F. McGUINNESS,
FILLING DETECTOR MECHANISM FOR WEFT REPLENISHING LOOMS.
APPLICATION FILED SEPT. 25, 1908.

943,702.

Patented Dec. 21, 1909.

2 SHEETS—SHEET 2.

UNITED STATES PATENT OFFICE.

BENJAMIN F. McGUINNESS, OF WORCESTER, MASSACHUSETTS, ASSIGNOR TO CROMPTON & KNOWLES LOOM WORKS, A CORPORATION OF MASSACHUSETTS.

FILLING-DETECTOR MECHANISM FOR WEFT-REPLENISHING LOOMS.

943,702.

Specification of Letters Patent. Patented Dec. 21, 1909.

Application filed September 26, 1908. Serial No. 454,748.

To all whom it may concern:

Be it known that I, BENJAMIN F. McGUINNESS, a citizen of the United States, residing at Worcester, in the county of Worcester and State of Massachusetts, have invented certain new and useful Improvements in Filling-Detector Mechanism for Weft-Replenishing Looms, of which the following is a specification.

10 My invention relates to a filling detector mechanism for weft replenishing looms, and particularly to a mechanical filling detector mechanism having a feeler, which is preferably located on the end of the lay, at the 15 magazine end of the loom, and at the rear of the stationary shuttle box at said end of the lay, and which is adapted to enter through an opening in the rear wall of the shuttle box, and through an opening in the 20 shuttle, to engage the filling on the bobbin in the shuttle, preferably at every other forward movement of the lay, and on the substantial or practical exhaustion of the filling in the active shuttle, operate mechanism connected with the weft replenishing mechanism, to cause a fresh bobbin to be supplied to the active shuttle, in place of the substantially exhausted bobbin, in the usual and well known way.

30 The object of my invention is to improve upon the filling detector mechanisms of the class referred to, and more particularly to provide a filling detector mechanism for weft replenishing looms, comprising two 35 members, both adapted to enter an opening in the shuttle, and engage the filling, and means to move one of said members relatively to the other member in the direction of the length of the bobbin, and connections 40 intermediate one of said members and the weft replenishing mechanism, to cause a fresh bobbin to be supplied to the active shuttle on the practical or substantial exhaustion of the filling on the bobbin in the 45 active shuttle.

In my improvements as shown and described herein I provide as one member of my filling detector mechanism, preferably a slide having a reciprocating movement, 50 which is moved into the shuttle in a direction at right angles to the axis of the bobbin to engage the filling on the bobbin, and is yieldingly held in contact with the filling.

I provide as the second member of my filling 55 detector mechanism, which is adjacent to

the first-mentioned member, preferably a second slide which is preferably supported on the first-mentioned slide, and is moved therewith, and is also moved in the direction of the length of the bobbin. When the first 60 mentioned slide engages the filling on the bobbin in the shuttle, it depresses the filling and causes the second mentioned slide, by its engagement with the filling, to be held in its inoperative position, but when the filling 65 on the bobbin is practically or substantially exhausted, the few layers of filling remaining on the bobbin will not be depressed sufficiently to prevent the transversely moving slide from operating, and an actuating 70 spring for said slide will move it along the filling of the bobbin, and put into operation the mechanism which operates the weft replenishing mechanism which may be of any ordinary construction.

75 My invention consists in certain novel features of construction of my improvements, which may be adapted to be applied to and used on any well known weft replenishing loom having a magazine for bobbins or filling carriers, either stationary, or movable.

80 I have only shown in the drawings a detached portion of a stationary shuttle box at the magazine end of a loom, with my improvements applied thereto, sufficient to enable those skilled in the art to understand the construction and operation thereof.

85 Referring to the drawings:—Figure 1 is a plan view of a detached portion of a stationary shuttle box with my improvements applied thereto, looking in the direction of arrow *a*, Fig. 5; some of the parts are broken away and others shown in section, and some parts shown in Fig. 5 are not shown in this figure. Fig. 2 is an underside view of the 90 parts shown in Fig. 1, looking in the direction of arrow *b*, Fig. 5. Fig. 3 corresponds to Fig. 1, but shows some of the parts in a different position. Fig. 4 is an underside view of the parts shown in Fig. 3. Fig. 5 is 95 a section, on line 5, 5, Fig. 1, looking in the direction of arrow *c*, same figure, and also shows a portion of the lay beam, and some other parts not shown in Fig. 1. Fig. 6 is a plan view, corresponding to Fig. 1, but 100 shows some parts in a different position, also shows some parts which are not shown in Fig. 1.

105 In the accompanying drawings, 1, Fig. 5, is a portion of the lay beam, 2 is a detached 110

portion of the back wall of a stationary shuttle box, 3 is a shuttle, carrying a bobbin 4, having filling 5 thereon. Secured on the rear side of the back wall 2 and extending out therefrom, is a stand 6, the upper side of which has undercut or grooved edges 6', see Figs. 2, and 4, which form a track or way for a slide 7, having a reciprocating movement toward and away from the filling in the shuttle, through an opening 2' in the back wall 2 of the stationary shuttle box, and an opening 3' in the rear of the shuttle 3. The engaging end of the slide 7 is preferably roughened or corrugated.

The slide 7 has a rearwardly extending arm 7', carrying at its end a pin 8, to which is connected one end of a helically coiled contraction spring 9; the other end of said spring 9 is connected to a pin 10 on a lever 11 having a hub 11' which is adjustably fastened by a set screw 12 on a vertically extending shaft 13, which has a bearing in a stand 14 secured to the back wall 2 of the stationary shuttle box. Extending out from the hub 11' of the lever 11 is an arm 11'' having pivotally connected thereto a rod head 15', on a rod or connector 15, see Fig. 6. The other end of the connector 15 has a rod head 15'' thereon, which is pivotally connected with one arm of an angle lever 16 having its hub 16' pivotally mounted on a stud 17 secured to the back of the lay, see Fig. 6. The other arm of the angle lever 16 carries a pin 16'', to which is pivotally connected the end of a connector 18, in this instance leading downwardly, and connected with operating parts of the loom, not shown.

Through the connector 18, angle lever 16, connector 15, and arm 11'', the lever 11 is rocked or moved at regular predetermined intervals, toward the stationary shuttle box, and through the spring 9, attached to said lever 11, the slide 7 will be yieldingly moved toward and into engagement with the filling 5 on the bobbin 4 in the shuttle 3. The backward or outward movement of the lever 11 will cause it to engage a pin or stud 7'' on the slide 7, and positively move back or outwardly said slide, to carry its inner engaging end out of and away from the opening through the shuttle 3, as shown in Fig. 6.

On the underside of the slide 7 is in this instance a screw 19, see Figs. 2 and 4, on which is loosely pivoted a three armed lever 20. One arm 20' of said lever 20 has a pin 21, see Figs. 2 and 4, to which is attached one end of a light helically coiled contraction spring 22. The other end of said spring 22 is attached to a pin 23 on the curved or cam shaped end 24' of an arm or lever 24. The hub 24'' of the lever 24 is secured by a set screw 25 on the lower end of the vertically extending shaft 13, see Fig. 5, to move with said shaft, which shaft is rotated or rocked by the arm 11'', and the con-

nections to said arm above described. The curved or cam shaped end 24' of the lever 24 is adapted to engage a pin 26 on the arm 20' of the three armed lever 20. On the three armed lever 20 is a second arm 20'', which extends toward the shuttle box, and has an elongated slot 20' therein, into which extends a pin 27 on the transversely moving slide 28, see Figs. 2, and 4. The slide 28 extends in this instance upon the underside 75 of the slide 7, and has an elongated slot 28' therethrough, through which extends a stud or pin 29, see Fig. 5, secured upon the underside of the slide 7, and having a head 29' which extends over the edges of the slot 28' 80 and acts to attach the slide 28 to the underside of the slide 7. A projection 28'' on the slide 28 extends in a notch or recess in the underside of the slide 7, at one edge thereof, see Figs. 2 and 4, and acts to hold the slide 85 28 relative to the slide 7, so that said slide 28 may have a transverse motion relative to the slide 7, or in a direction at right angles to the motion of the slide 7, and also in a direction lengthwise of the bobbin 4 having the 90 filling 5 thereon.

The slide 28 has an engaging end 28' thereon, which is preferably made inclined, as shown, and also preferably roughened or corrugated and is adapted to engage with 95 the filling 5 on the bobbin 4, when the slide 7 is moved toward the bobbin, as shown in Fig. 4. The engaging end of the slide 28 preferably does not extend to the extreme end of the slide 7.

The stand 6 has an elongated opening 6' therethrough, through which extends a pin 30, which is adjustably secured in said opening by a nut 30', see Figs. 2 and 3. The pin 30 has in this instance a square shaped 105 lower end, see Figs. 2 and 4, which is adapted to engage the outer edge of the arm 20'' of the lever 20, as long as there is a certain amount of filling 5 on the bobbin 4, see Fig. 2, to prevent the slide 28 from moving side- 110 wise. On the three armed lever 20, a third arm 20''' carries a pin 31, which extends into an elongated slot 32' in a lever 32, having the hub 32'' pivotally mounted on a screw 33 secured upon the upper side of the 115 stand 6. The outer end of the lever 32 has in this instance a stud 32' thereon, which is adapted to be moved into the path of a lever 34, shown in section, in Figs. 1, and 3, to move said lever, on the forward movement of the lay, and cause it, through intermediate connections, not shown, of any usual and ordinary construction in weft replenishing looms, to put into operation the weft replenishing mechanism, to supply a fresh 120 bobbin in place of the substantially exhausted bobbin, in the usual way.

Fast on the connector rod 15, see Fig. 6, is a collar 35, having an extension 35' thereon, which extends in the path of and is 130

adapted to engage an arm 36, having its hub 36' fast on the shaft 37, which is loosely mounted in a bearing 2" on the back wall 2 of the stationary shuttle box. Fast on the 5 other end of the shaft 37 is the hub 38' of an arm 38. The arm 38 extends upwardly from said shaft 37, (see Fig. 5,) and is adapted to be engaged by the transerrer arm, not shown, of the transferring mechanism, not shown, or other suitable mechanism, when the bobbin is being transferred, to cause, through the movement of said lever 38, shaft 37, and arm 36, the movement of the connector 15, and through arm 10 11", the movement of the arm 11, to cause it to engage the pin 7" on the slide 7, and move said slide away from and out of the shuttle, as shown in Fig. 6.

From the above description in connection 20 with the drawings the operation of my improvements will be readily understood by those skilled in the art.

When the bobbin has a sufficient supply of 25 filling thereon, as shown in Figs. 1, 2, and 5, the engagement of the engaging end of the slide 7 with said bobbin, through the movement of the arm 11, and its operating mechanism, and the spring 9, at regular predetermined intervals, preferably at every 30 other forward movement of the lay, will form a slight depression in the filling on the bobbin, and will carry the engaging end 28" on the transverse slide 28 into engagement with the filling, and the friction of said end 35 with the filling, will hold the slide 28, as shown in Figs. 1, 2, and 5, and prevent any transverse movement thereof, relative to the slide 7, until the filling on the bobbin is substantially exhausted.

40 When the filling 5 on the bobbin 4 is practically or substantially exhausted, as shown in Figs. 3 and 4, the increased movement of the slide 7, carrying the lever 20 thereon, will cause the edge of the arm 20" of said 45 lever to pass by the stud 30, and as there is not sufficient filling on the bobbin to hold the engaging end 28" of the slide 28, the light spring 22 will act, to move the lever 20" toward the left, Fig. 4, until the pin 26 50 engages the cam shaped end 24" of the arm 24, and also move the arm 20", and through the pin 31 thereon, the lever 32 will be moved, to carry the stud 32" thereon into the path of the lever 34, see Fig. 3, so that on the 55 forward movement of the lay said lever 34 will be operated, and through connections to the weft replenishing mechanism, will put into operation said mechanism, to supply a fresh bobbin in place of the substantially exhausted bobbin.

It will be understood that the details of construction of my improvements may be varied if desired.

I do not limit my invention to the particular form and construction of the filling de-

tector mechanism shown and described, as my invention is intended to cover broadly, a filling detector mechanism for weft replenishing looms, comprising two adjacent members, both adapted to enter an opening 79 in the shuttle and engage the filling, and means to move one of said members relatively to the other, in the direction of the length of the bobbin, to cause the operation of the weft replenishing mechanism on the 75 practical or substantial exhaustion of the filling in the active shuttle.

Having thus described my invention, what I claim as new and desire to secure by Letters Patent is:—

80

1. In a filling detector mechanism for weft replenishing looms, a slide having a movement in a direction at right angles to the axis of the bobbin in the shuttle, and adapted to enter an opening through the 85 shuttle and to engage the filling on the bobbin, and a second slide mounted on and moving with said first mentioned slide, and adapted to enter an opening through the shuttle, and to engage the filling on the 90 bobbin, and also having a movement in a direction at right angles to the direction of movement of the first mentioned slide.

2. In a filling detector mechanism for weft replenishing looms, a slide having a 95 movement in a direction at right angles to the axis of the bobbin in the shuttle, and adapted to enter an opening through the shuttle and to engage the filling on the bobbin, and a second slide mounted on and moving with said first mentioned slide, and adapted to engage the filling on the bobbin, and also have a movement in a direction at right angles to the direction of movement of the first mentioned slide, and means for 105 yieldingly moving the first mentioned slide to cause it to enter the shuttle and engage the filling, and means to positively withdraw said slide from the shuttle.

100

3. In a filling detector mechanism for 110 weft replenishing looms, a slide having a movement in a direction at right angles to the axis of the bobbin in the shuttle, and adapted to enter an opening through the shuttle and to engage the filling on the bobbin, and a second slide mounted on and moving with said first mentioned slide, and adapted to engage the filling on the bobbin, and also have a movement in a direction at 115 right angles to the direction of movement of the first mentioned slide, and means for moving the second mentioned slide relatively to the first mentioned slide, and in a direction lengthwise of the bobbin, and connections intermediate said second mentioned 120 slide and mechanism connected with the weft replenishing mechanism, to put into operation said weft replenishing mechanism.

125

4. In a filling detector mechanism for a weft replenishing loom, the combination 130

with a slide having a reciprocating movement, in a direction at right angles to the axis of the bobbin in the shuttle, and means for moving said slide in and out through an opening in the shuttle, to engage and be disengaged from the filling, of a second slide mounted on said first mentioned slide, and movable therewith, to engage the filling and to be disengaged therefrom, and also on the substantial exhaustion of filling to be moved in a direction lengthwise of the bobbin and at right angles to the direction of movement of the first mentioned slide, and mechanism connected with said second mentioned slide to put into operation the weft replenishing mechanism.

5. In a filling detector mechanism for a weft replenishing loom, the combination with a slide having a reciprocating movement in a direction at right angles to the axis of the bobbin in the shuttle, and means for moving said slide in and out through an opening in the shuttle, to engage and be disengaged from the filling, of a second slide mounted on said first mentioned slide and movable therewith, to engage the filling and be disengaged therefrom, and also on the substantial exhaustion of filling to be moved in a direction lengthwise of the bobbin and at right angles to the direction of movement of the first mentioned slide, and mechanism connected with said second mentioned slide, to put into operation the weft replenishing mechanism, and mechanism to move both slides away from and out of the shuttle, when a bobbin is being transferred.

6. In a filling detector mechanism for weft replenishing looms, a slide having a reciprocating movement toward and away from the filling in the active shuttle, and adapted to enter an opening through the shuttle and to engage the filling on the bobbin, and a second slide mounted on and mov-

ing with said first mentioned slide, and adapted to enter an opening through the shuttle and to engage the filling on the bobbin, and also having a movement in the direction of the length of the bobbin.

7. In a filling detector mechanism for weft replenishing looms, carried on and movable with the lay, a slide having a reciprocating movement toward and away from the filling in the active shuttle, and adapted to enter an opening through the shuttle and to engage the filling on the bobbin, and a second slide mounted on and moving with said first mentioned slide, and adapted to enter an opening through the shuttle and to engage the filling on the bobbin, and also having a movement in the direction of the length of the bobbin.

8. A filling detector mechanism, comprising two adjacent members, both adapted to enter an opening in the shuttle and engage the filling, and means to move one of said members relative to the other, in the direction of the length of the bobbin, to cause the operation of the transferring mechanism on the practical or substantial exhaustion of filling in the active shuttle.

9. A filling detector mechanism, comprising two adjacent members, both adapted to enter an opening in the shuttle and engage the filling, and means to move one of said members relative to the other, in the direction of the length of the bobbin, and connections intermediate said member and the weft replenishing mechanism, to cause the operation of the weft replenishing mechanism on the practical or substantial exhaustion of filling in the active shuttle.
